UNITED STATES PATENT OFFICE.

CARL WINKLER, OF BERNE, SWITZERLAND.

METHOD OF MAKING STEREOGRAPHIC-MATRICES.

1,333,361.

Specification of Letters Patent.

Patented Mar. 9, 1920.

Application filed January 4, 1917. Serial No. 140,602.

To all whom it may concern:

Be it known that I, CARL WINKLER, a citizen of the Swiss Republic, resident at Berne, in the Swiss Republic, have invented 5 an Improved Method for Making Stereotype-Matrices, of which the following is a specification.

This invention relates to an improved method for making stereotype matrices.

10 Heretofore it was usual, in making stereotype matrices in a press, to dry said matrices under the high pressure at which they are imprinted. For this purpose the driving motor of the press was put out of gear or stopped when the press head had reached its lowest position. This method, however, has the drawback that the type, or the like, is injured by the united action of the pressure and heat.

15 In my patent application No. 41120 of 1915 I have described a mechanical matrix-imprinting press, in which reduced pressure is brought to bear upon the matrix, by a special device, just after the maximum pressure has ceased to act on the matrix.

20 It will be understood, that the mentioned method can be used without providing the imprinting press with automatically actuated devices for this purpose.

25 According to my present invention the before mentioned drawback is overcome by imprinting the matrix, as heretofore, at a high pressure, and by then drying said matrix at a reduced pressure. In other words, the press is not stopped for drying the matrix until the press-head, or the like, has passed, or retreated from, the point of highest pressure, that is, this will only be the case if the press is turned off at high pressure, turned on again after a little while and turned off when the pressure is less. Thus the pressure on the matrices is released or reduced just after maximum pressure.

30 In the accompanying drawings in which a press adapted to carry out my invention is shown by way of example,

Figure 1 is a side elevation of the press, and

35 Fig. 2 is a top plan view of the same with the work table removed.

The embodiment of mechanism for carrying out my invention which is illustrated, comprises an electric motor *a* which drives the worm *c* through the clutch *b*. This worm

engages a worm-wheel *d*, the rotation of which is imparted through the spur-wheels *e*, *f* and *g*, to the crank-wheel *h*. The crank-wheel through the agency of the connecting rod *i*, moves the toggle *k* and thus alternately raises and lowers the press head *l*. 55 60

On the shaft *m* of the crank-wheel *h* is fastened a cam *n*, which twice in every revolution, operates a detent lever *o* to release the lever *p*, the consequent movement of which disengages the clutch *b*, thereby stopping the vertical movement of the press head. 65

The protuberances upon the cam *n* which operate the lever *o* are so positioned as to cause one protuberance to operate said lever 70 and thereby stop the press just after the maximum pressure has been exerted by the press head, or in other words to stop the press in such a position as to exert a slightly less than maximum pressure upon the 75 matrix; and to cause the other protuberance to operate lever *o* and stop the press when the press head has reached its highest position.

By this arrangement it will be seen that 80 the press is stopped after the maximum pressure has been exerted to form a matrix, and the matrix is allowed to dry while subjected to this somewhat less than maximum pressure; and when it is desired to remove 85 the matrix the press is stopped at its other stop position, that is, at its highest point of movement.

A matrix is thus adapted to be formed by exerting maximum pressure to imprint 90 the same and then subjecting the matrix to a somewhat lower pressure while it is drying.

What I claim and desire to secure by Letters Patent of the United States is: 95

An improved method for making stereotype matrices, consisting in imprinting the matrix under pressure, releasing the pressure slightly, and drying the matrix while under the lower pressure. 100

In testimony whereof I have signed my name to this specification in the presence of two subscribing witnesses.

CARL WINKLER.
